COMBINATION TOILET BOWL BASE AND FLUSH LEVER

Robert F. O'Brien, 1840 N. Garfield, Apt. 110,
Los Angeles, Calif.

Filed July 27, 1960, Ser. No. 61,541

Term of patent 14 years

(Cl. D4—5)

Figure 1 is a perspective view of a combination toilet bowl base and flush lever showing my new design;

Figure 2 is a right side elevational view thereof, the left side being substantially the same.

Figure 3 is a top plan view thereof;

Figure 4 is a rear elevational view; and

Figure 5 is a front elevational view thereof.

I claim:

The ornamental design for a combination toilet bowl base and flush lever, substantially as shown and described.
